CLAIM

The ornamental design for a controller for electronic equipment, as shown and described.

DESCRIPTION

FIG. 1 is a perspective view of the controller for electronic equipment, showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof, shown in an alternate state for use.

The broken lines in FIG. 8 showing the alternate state depict environmental subject matter only and form no part of the claim, while all other broken lines depict portions of the controller for electronic equipment that form no part of the claimed design.

The controller for electronic equipment according to the present design is installed on a screen driving range and used to manipulate screen golf.
